UNITED STATES PATENT OFFICE.

WILLIAM H. FINK, OF DIAGONAL, IOWA.

RECORD-REPEATING DEVICE FOR TALKING-MACHINES.

1,331,702.

Specification of Letters Patent. Patented Feb. 24, 1920.

Application filed June 24, 1918. Serial No. 241,571.

To all whom it may concern:

Be it known that I, WILLIAM H. FINK, a citizen of the United States, residing at Diagonal, in the county of Ringgold, State 5 of Iowa, have invented a new and useful Record-Repeating Device for Talking-Machines; and I do hereby declare the following to be a full, clear, and exact description of the invention, such as will enable others 10 skilled in the art to which it appertains to make and use the same.

This invention relates to the art of talking machines, and particularly to an improved record repeating device, and one of 15 the objects of the invention is to provide an improved mechanism of this kind having tone arm shifting means, and a device actuated by the tone arm for releasing said means, whereby said means may be actuated 20 by a member engaging the center portion of the record, to move said means so that it may lift and return the tone arm to its initial position.

A further object of the invention is to 25 provide means for stopping the turn table at the completion of a plurality of repetitions of the record.

A further object of the invention is the 30 provision of means adapted to be adjusted, and to be actuated by the tone arm between different predetermined points of movements of the tone arm, whereby records of different diameters with pieces thereon of different 35 lengths may be played, and consecutively repeated.

A further object of the invention is the provision of means for adjusting the member, which engages the turn-table, so as to 40 permit said member to engage the record at the proper time, in order that it may actuate said tone arm shifting means, whereby said means may return the tone arm, to an initial position on the record.

In practical fields the details of construction 45 may necessitate alterations, and the right to make such alterations as may be necessary is reserved, provided the alterations fall within the scope of what is claimed.

50 The invention comprises further features and combination of parts as hereinafter set forth shown in the drawings and claimed.

In the drawings:—

Figure 1 is a plan view of a conventional 55 form of cabinet-talking machine, showing the record supporting table, the tone arm

with its sound box, and the automatic repeating device as applied.

Fig. 2 is an enlarged detail view of the means carried by the repeating device for 60 limiting the repetition of the record.

Fig. 3 is an enlarged detail perspective view of the repeating apparatus detached.

Fig. 4 is a view in side elevation of said apparatus, showing a revoluble member just 65 in the act of engaging the record on the turn-table.

Fig. 5 is a view in side elevation of the repeating apparatus, showing the revoluble member as having been rotated almost a 70 complete revolution.

Fig. 6 is a detail view of a portion of the supporting beam for the revoluble member, showing the support for said beam.

Fig. 7 is a detail view of the mounting 75 of the brake-shoe for the turn-table.

Fig. 8 is a longitudinal sectional view through the tubular beam for the support of the shaft of the revoluble member, which 80 engages the record.

Fig. 9 shows a detail, sectional view of 85 part of the pivot mechanism.

Referring more especially to the drawings 1 designates a conventional form of talking machine cabinet, which is designed to contain the operating mechanism (not shown) 85 for the turn-table 2, which is carried by the center shaft 3, to which revoluble movement is imparted by the mechanism (not shown). A suitable record 4 is shown as mounted on 90 the turn-table, and 5 denotes a tone-arm, which is pivoted on the cabinet as at 6, so as to have a communicative connection (not shown) with the amplifier (not shown) but designed to be ordinarily carried in the 95 cabinet. The tone arm has the usual sound box 7, which is provided with a stylus 8 to play in the sound groove of the record at 9.

Secured by means of screws or the like 10 to the cabinet 1 is a base plate 11, and 100 rising upwardly from the plate is a standard 12, the upper end of which is provided with a right angle extending tubular portion 13. One end of this tubular port 13 has an inclined slot 14, the inner end of 105 which terminates in an enlargement 15. Supported in the tubular portion 13 is a beam or arm 16, and which beam or arm is provided with a lateral pin 17, normally 110 engaging the enlargement 15 of the slot 14. Mounted in the tubular portion 13 is a coil spring 18, one end of which engages one

end of the interior of said tubular portion 13 as at 19, and the other end portion of said spring bears against one end of the tubular arm or beam 16. By means of this 5 spring the pin 17 is held normally in engagement with the shoulder 21 of the enlargement 15 of the slot 14. Rising upwardly from the tubular portion 13 is a lug 22, in which a thumb screw 23 has its shank 10 bearing against the pin 17, so that by adjusting the thumb screw 23 in one direction or the other, the tubular arm or beam 16 may be adjusted slightly rotatably in the tubular portion 13. The end part 24 of the 15 tubular arm or beam 16 is provided with a lateral beam or arm 25, and mounted in the beam or arm 25, is a shaft 26. One end of the shaft 26 has a crank arm 27, and the other end is provided with a disk 28. The 20 hub of the disk is secured to the shaft 26 by means of the pin 29. Between the disk 28 and a second disk 30 a disk wheel 31 is clamped by means of the pins 32. The circular marginal edge of the disk wheel has 25 secured to it in any suitable manner a rubber band or the like 33. This disk wheel 31 has a segment portion thereof flattened as shown at 34. The base plate 11 supporting the upright or standard 12 is disposed so that the disk wheel 31 may be supported with its flattened portion 34 in front of and as close to the center post of the turn table as possible, without touching either the post or the record. For instance as shown in 30 Fig. 1, the record has a central part 35 which is minus the sound groove, in fact this central part is a plane surface, and the rubber ring 33 is designed to engage this surface, as will be explained later. However, the 35 supporting plate 11, the upright 12 and the arm or beam 16 are disposed, whereby the beam or arm 25 may extend across the center post or shaft 3, and support the disk wheel, so as to permit freedom of movement of the 40 tone-arm in its travel across the record, that is without contacting of the sound box with the disk wheel. It is to be noted that by adjusting the thumb screw 23 the arm or beam 16 is adjusted rockably in the tubular portion 13, in order to regulate the distance between the flat portion 34 of the disk wheel 31 and the plane surface of the record. Pivoted at 35^a to the arm or beam 16 is a trigger plate 36, which is angular in cross section. The two lugs 37 of this plate engage 45 under the arm or beam 16, so as to limit the trigger plate in its rocking movement in one direction or the other. The central angular arm 38 which depends downwardly from the 50 trigger plate between the arms or lugs 37 has its lateral portion 39 arranged to support the crank arm 27, as shown clearly in Figs. 1 and 3. A leaf spring 40 is attached in any suitable manner as at 41 to the arm or beam 16, and has its free end engaging 55 one of the lugs 37 as at 42, thereby acting to hold the other lug 37 normally in contact with the beam or arm 16. The pin 17 is provided with a lateral part terminating in a guide eye 43, in which the rod 44 reciprocates. This rod 44 is pivoted to the lateral end 45 of the crank arm 27. An extension 46 is pivoted at 47 to the trigger plate 36. This pivot 47 is of such construction as to frictionally bind the extension 46 and the trigger plate. In other words the extension when moved will be held frictionally in position. A loop or member 48 is mounted upon the beam or arm 16, and is provided with an upstanding screw 49, 60 provided with a thumb head 50. By means of this screw 49, the loop or member 48 may be held in different adjusted positions on the arm or beam 16. The loop or member 48 and the extension 46 may be adjusted, so 65 that the tone-arm will play or move between the extension 46 and the screw 49, according to the terminals of the sound groove of the record. For instance the tone-arm after having once been set in contact with the 70 screw 49, and the stylus of the sound box at the starting of the sound groove, moves across the record, and when the stylus reaches the inner terminal of the sound groove, the tone arm will contact with the 75 extension 46. The frictional contact between the extension 46 and the trigger plate is sufficient to withstand the tension of the spring 40. When the trigger plate 36 is tilted, by the arm contacting with the extension 46, the lateral part 39 of the lug or 80 arm will be moved out of the path of the end of the crank arm 27, in which case the weight of the crank arm 27 will over-balance the disk wheel, so that the disk wheel 85 100 at the point indicated at 51 will engage the plane central surface of the record, and since the record and the turn table are still rotating, the disk wheel will receive revoluble movement from the record. Consequently 105 the shaft 26 will be rotated, also the crank arm 27, and as the lateral part 45 of the crank arm approaches a position above the shaft 26, the rod 44 will engage and lift the tone-arm, and raise the sound box upwardly 110 115 from the record. When the lateral part 45 of the crank arm 27 starts to rise above the shaft 26 the rod 44 will continue to lift the tone arm until the lateral part 45 is returned to engagement with the lateral portion 39. 120 When the end of the rod 44 connected with the end 45 of the crank arm 27 is swung in a circle by the movement of the disk and the crank arm, the tone arm is raised and carried toward the screw "49", with the stylus of the sound box in position to engage the beginning of the sound groove of the record. The tone arm may be shifted as 125 many times as may be permitted according to the strength and action of the spring of 130

the motor (not shown), and if the motor is re-wound each time that it runs down, the tone-arm may be shifted substantially indefinitely.

- 5 However, a device is carried by the standard or post 12 of the repeating mechanism, for limiting the shifting of the tone arm to a predetermined number of times. For instance a record may be repeated five times
 10 and at the end of the 5th time a brake device may be applied to the circular marginal edge of the turn-table. This device for limiting the repeating of a record comprises an angular plate 52 which is secured
 15 in any suitable manner to the post or standard 12, and has a lateral portion 53. This lateral part is provided with a slot 54. The lower edge of the slot 54 is provided with ratchet teeth 55, which are V-shaped. The
 20 upper wall of the slot 54 is provided with depending elongated teeth 56 provided with beveled ends 57. An arm 58 projects from the plate 52 and its end portion carries an upright pivot pin 59. A plate 60 is pivotally
 25 mounted upon the pin 59 and has a brake foot 61 at one end, said foot having a brake shoe 62, for contact with the circular marginal edge of the turn table. The other end of the plate 60 has a roll or bent-over end
 30 63, which carries an arm 64. A coil spring 65 is mounted upon the pin 59, so that its lower end will bear on the plate 60. The upper extremity of the spring 65 engages through an aperture 66 of the upper end of
 35 the pin 59 and its lower extremity engages one end of the roll 63 as at 67, acting to urge the shoe 62 toward the record disk. The shoe 62 is normally held away from contact with the record disk by the engagement
 40 of the arm 64 on the roll 63 with one of the ears 68 or 69 of the plates 70, which are welded to or otherwise carried by the lower part of the lateral portion 53 of the plate 52. These ears 68 and 69 are in parallelism, and mounted rockably in said ears are the crank ends 71 and 72 of the elongated tripping loop or rod 74. This tripping loop or rod 74 rests upon the upper edges of the plates 70. The crank end 72
 45 of the tripping loop or rod has an upstanding arm 75. The guide rod 44 at one end has a loop 76 provided with a hook 77. Each time the guide rod 44 is actuated to a position for returning the tone-arm, and finally
 50 assumes a position as shown in Fig. 3, the hook 77 contacts with the arm 75 for tripping the same. The spring 65 not only acts to hold the arm 64 in engagement with the straight portion of each ratchet tooth, but
 55 also acts to hold the arm 64 between the teeth. When the arm 75 is tripped, the trip bar or loop 74 is tilted upwardly raising the arm 64 against the action of the spring 65. The teeth 56 are arranged so that
 60 their lower terminals (which are beveled)
- are opposite the spaces between the ratchet teeth. It is to be noted that when the arm 64 is raised, it will slide upwardly past the adjacent ratchet tooth on the lower wall of the slot, and will then contact with the end 70 portion of the adjacent depending tooth 56, and will remain so engaged, until the hook 77 will disengage or pass by the arm 75. The arm 64 will then, owing to the action of the spring 65 and the force of gravity, 75 move downwardly and engage the next ratchet tooth. It is to be noted that there are enough teeth so as to permit the arm 64 to escape from one to the other intermittently, thereby moving the brake-shoe 80 intermittently toward the turn table, and to permit the record to repeat five consecutive times, and when the stylus reaches the end of the record at the fifth repetition of the record the brake-shoe will contact with the 85 circular marginal edge of the turn-table, thereby stopping the machine. One of the teeth 56 is provided with a hook 78 and may be engaged by the arm 65 so as to hold the brake shoe constantly out of contact 90 with the turn table, in fact, so that the tone-arm may be shifted and the record repeated as many times as may be permitted by the strength of the spring of the motor.
- The invention having been set forth what 95 is claimed as new and useful is:—
1. The combination of a swinging tone arm and a revoluble record with a supporting member, a shaft mounted therein, a disk on said shaft having a flattened edge, an arm 100 on said shaft, a rod pivoted to said arm for swinging and sliding movement, a catch device adapted to normally stand in position for holding said arm in position for maintaining the disk with its flattened edge 105 downward, an engaging member on said catch device adapted to be engaged by the tone arm for causing the catch device to disengage the arm on said shaft for permitting it to drop downwardly to thereby cause the 110 disk to engage said record, whereby said rod is caused to raise said tone arm and swing it to a different position.
  2. A combination of a swinging tone arm and revoluble record with a shaft, a disk 115 thereon having a flattened edge, an arm on said shaft, means for normally holding said arm in position with the flattened edge of the disk downward, said means being adapted to be disengaged by the moving of 120 said tone arm for causing the disk to engage the record, and means actuated by the rotation of said disk in contact with said record for raising and swinging said tone arm to another position.
  3. The combination of a swinging tone arm and a revoluble record with a supporting member, a shaft rotatably mounted therein, a disk on said shaft having a flattened edge, an arm on said shaft, a catch 125
- 130

device for said arm adapted to be disengaged by said tone arm when the tone arm swings to one position of its movement, means whereby the rotation of said disk carries said tone arm from one position to another.

4. The combination with a revoluble record, of a tone arm to swing across the record, and a mechanism actuated by the record to return the arm to its starting position, and brake means to be actuated intermittently by said mechanism to engage the record supporting table subsequently to predetermined repetitions of the record, said

brake means comprising a brake lever having a brake shoe, spring tensioned means for the brake lever, an escapement mechanism for the brake lever, and a tripping device actuated by the mechanism operated by the record for operating the escapement mechanism.

In testimony whereof I have signed my name to this specification in the presence of two subscribing witnesses.

WILLIAM H. FINK.
